UNITED STATES PATENT OFFICE.

FREDRICK PHILIP KREMER, OF MARIETTA, OHIO.

MOTOR.

SPECIFICATION forming part of Letters Patent No. 340,586, dated April 27, 1886.

Application filed January 30, 1886. Serial No. 190,385. (No model.)

To all whom it may concern:

Be it known that I, FREDRICK PHILIP KREMER, a citizen of the United States, residing at Marietta, in the county of Washington and 5 State of Ohio, have invented certain new and useful Improvements in Motors for Rocking Cradles or Analogous Uses; and I do declare the following to be a full, clear, and exact description of the invention, such as will enable 10 others skilled in the art to which it appertains to make and use the same, reference being had to the accompanying drawings, and to the letters and figures of reference marked thereon, which form a part of this specification.

15 The general object of the invention is to produce a spring-operated motor, which may be conveniently used for giving a vibratory or rocking motion, and my special object is to rock a cradle at greater or less speed without 20 the continuous attention of any person after it has been started.

Figure 1 of the drawings is a front elevation of the clock-work; Fig. 2, a transverse vertical section of the pitman and rockers of the 25 cradle, and Fig. 3 a view of the immediate drive mechanism attached to the rockers in side elevation.

In the drawings, A represents a shaft driven by a coil-spring, which is wound up and operates in the usual way to turn the shaft. The 30 shaft A turns a pinion on shaft A', so as to cause wheel 1 to rotate it and thereby turn wheel 2. The latter, in like manner, meshes with a pinion on shaft A', so as to turn it with

the wheel 3, while the wheel 3 meshes with a 35 pinion on the shaft B, for the purpose of rotating the wheel B'. The wheel B' is provided with a crank-pin, b, which works in a slot, c, of the pitman C, which is attached by means of a plate, D, with the cradle E. The upper 40 part of the pitman C is secured to a plate, F, having two or more holes, f, in either of which may be fastened to the plate G on a support, I, a screw-pivot, H, on which said pitman turns.

45 As the pitman is vibrated the cradle E is rocked and its velocity made greater or less, according to which hole f receives the pivot H.

I preferably box the mechanism to prevent accident and the access of dust to working 50 parts.

Having thus described all that is necessary to a full understanding of my invention, what I claim as new, and desire to protect by Letters Patent, is—

55 The combination, with a clock mechanism, substantially as described, of the wheel B', having crank-pin b, the pitman C, having the slot c, the plate D, attached to the cradle E, the plate F, having holes f, the screw-bolt H, the plate G, and the support I, substantially as shown and described.

60 In testimony whereof I affix my signature in presence of two witnesses.

FREDRICK PHILIP KREMER.

Witnesses:

JAMES T. MITCHELL,
A. D. FOLLETT.
